UNITED STATES PATENT OFFICE

2,303,667

TOOTHBRUSH

Alfred F. Taborski, Bradford, Pa.

Application August 9, 1940, Serial No. 352,018

3 Claims. (Cl. 15—128)

This invention relates to an improved tooth brush and seeks, among other objects, to provide a brush of this character having a head and a handle formed with channels for receiving water and dentifrice to be discharged between tufts of bristles on the head of the brush during a tooth cleaning operation.

Another object of the invention is to provide a tooth brush having improved setting means for the tufts of bristles.

A further object of the invention is to provide a tooth brush which, in one embodiment, employs a separable head and handle structure.

A further object of the invention is to provide a tooth brush having channels, one of which will be connected to a source of water and the other of which will be connected with a source of dentifrice, said channels leading the water and the dentifrice, through openings in the head of the brush, to the bases of the bristle tufts.

Another object of the invention is to provide a tooth brush which, in one embodiment, is formed with a flexible tube mounted on the handle thereof substantially intermediate the length of said handle for supplying dentifrice to the bases of the bristle tufts for a tooth cleaning operation.

As a still further object, the invention seeks to provide a tooth brush wherein either or both of the channels may be connected with a source of water for the purpose of cleaning said channels and removing any obstructions therein.

And a still further object of the invention is to provide, in a slightly modified embodiment, a tooth brush having bristle tufts which are removably mounted in the handle so that, when the bristles of said tufts become too soft for effective use, said bristle tufts may be removed and new ones substituted therefor without the need of destroying the handle.

Other objects of the invention not particularly mentioned hereinbefore will become apparent during the course of the following description.

In the accompanying drawings:

Figure 1 is a side elevation of my improved tooth brush.

Figure 2 is a longitudinal sectional view on the line 2—2 of Figure 1, looking in the direction of the arrows.

Figure 3 is a longitudinal vertical sectional view showing a modified form of tooth brush.

Figure 4 is a detail sectional view showing another modified construction.

Figure 5 is a side elevation, partly shown in 55

section, of a slightly modified embodiment of my invention.

Figure 6 is a longitudinal sectional view on the line 6—6 of Figure 5, and

Figure 7 is a vertical transverse sectional view, on an enlarged scale, on the line 7—7 of Figure 6.

Referring now to the drawings and particularly to Figures 1 and 2 thereof, the numeral 1 indicates the body of my improved tooth brush.

10 The body includes a substantially flat handle 2 and an enlarged head 3. Projecting downwardly from the head 3 is a group of bristle tufts 4 which are set in substantially funnel-shaped mountings 5 which surround discharge openings 6 formed in the head.

By referring to Figure 2, it will be seen that I provide parallel channels 7 and 8 which extend throughout the length of the body 1. That is to say, said channels extend throughout the 20 length of the handle and throughout the major portion of the length of the head 3. The channels are closed at their corresponding forward ends by a stop wall 9. A partition 10 extends throughout the length of the body and effectually prevents communication between the channels 7 and 8. The channels 7 and 8 communicate with the openings 6 and, in this connection, it is desired to call attention to the fact that there are but two of the openings 6 communicating with the channel 7, these two openings being located near the forward end of said channel and being in spaced relation with respect to each other. For the sake of convenience, these two openings will be designated by the numeral 6^a.

25 The openings 6^a are for the purpose of discharging dentifrice from the channel 7 to flow or pass about the bases of the bristle tufts 4. During a tooth cleaning operation, the dentifrice will be caused to come in contact with and effectually cleanse the teeth.

The openings communicating with the channel 8 are designated by the numeral 6^b. These openings are arranged along the entire length of the head in longitudinally spaced relation and 45 are for the purpose of leading water or other liquid to the bases of the bristle tufts. The funnel-shaped mountings 5 will effectually direct the liquid or dentifrice to the bases of the bristle tufts 4.

50 Fitted into the channels 7 and 8, at the free end of the handle 2, are couplings 11 and 12. The couplings provide effective means whereby flexible tubes 13 and 14 may be connected to the channels 7 and 8.

In use, dentifrice is led through the tube 13

into the channel 7. The dentifrice will pass through the channel 7 and through the openings 6^a to the bases of the bristle tufts 4. A flow of water or other liquid may be caused to pass through the tube 14 and channel 8 to discharge through the openings 6^b. Thus, with a source of dentifrice and a source of water or other liquid at hand, it will be possible for a person to clean his or her teeth in a highly efficient and sanitary manner.

Attention is directed to the fact that, if necessary, the tube 13 may be removed from the coupling 11 and the tube 14 connected thereto. A flow of water through the tube 14 will pass into the channel 7 and effectively flush said channel and the openings 6^a, in the event clogging takes place. After flushing, the tube 14 may be removed and placed on its proper coupling 12 and the tube 13 replaced on the coupling 11.

It is further desired to call attention to the fact that the partition 10 will effectually prevent mixing of the dentifrice and liquid before discharge thereof about the bases of the bristle tufts.

By referring to Figure 3 of the drawings, it will be seen that I have provided a slightly modified construction. The modification of the invention as disclosed in Figure 3, includes a body 15 having a handle 16 and a head 17. The body 15 is of identical construction with the body 1 with the following exception. The dentifrice channel, indicated at 18, is formed with an inlet bore 19 which communicates with a preferably circular, flexible rubber container tube 20 which is formed on or secured to the under side of the handle 16 rearwardly of the head 17. The tube 20 is formed with a threaded neck 21 which receives a screw cap 22. In this embodiment of the invention, there is provided a channel parallel to the channel 18 but isolated therefrom, for supplying liquid to the bases of the bristle tufts. In use, it is only necessary for a user to compress the tube 20 for forcing dentifrice to flow about the bases of the bristle tufts, for a tooth cleaning operation. As will be seen, the channel 18 extends throughout the length of the handle and is formed with a socket 23 to receive a coupling so that the flexible tube from the water supply may be connected with said channel 18 for flushing said channel and removing obstructions therein.

Referring now to the modification of the invention disclosed in Figure 4, the numeral 24 indicates the head of a tooth brush made in accordance with the modified construction. The head 24 includes bristle tufts 25 which are set in funnel-shaped mountings 26. The head 24 is formed with an enlarged socket 27 which removably receives a reduced neck 28, said neck being formed on the forward end of a handle portion 29. This construction enables the user to remove the head from the handle when it is desired to clean the head with bristles attached thereto. Also, should it be necessary to replace either the head or the handle, this may be done conveniently.

In Figures 5, 6 and 7, I have shown a still further modified embodiment of the invention. In these views, the numeral 30 indicates the body of this embodiment of the invention, said body having a handle 31 and a head 32. The head 32 is formed with a plurality of openings 33 which are circular and are threaded. The openings are arranged in the same manner as are the openings 6^a and 6^b in Figures 1 and 2 of the drawings. Said

openings 33 are, however, considerably larger in size.

At 34, I have shown the base of one of my improved bristle tufts, said tufts being shown generally at 35. The tufts 35 are of identical construction so that a description of one will suffice for all of them. Each of the tufts includes, in addition to the base 34, bristles 36. Also, a discharge pipe 37 is mounted axially of the bristles and extends into communicating relation when one of the openings 33 and one of the passages 39 or 40 which are formed in the body 30 extend longitudinally thereof. The pipe 37 is suitably secured to the base 34, said base having an opening axially thereof to permit flow of liquid into said pipe 37. The base is externally threaded to screw into the threaded opening 33. It will now be understood that, when either water or dentifrice is caused to flow through the passages 39 and 40, said water or dentifrice will pass through the openings in the base 34 and through the pipe 37 for discharge near the ends of the bristles 36. The water or dentifrice will thus flow to the place where it will do the most good. When the bristles 36 become soft, after continued use, it is only necessary to unscrew the bases 34 in the opening 33, when the tufts 35 may be removed and new ones inserted.

Having thus described the invention, what is claimed as new is:

1. A tooth brush including a body having a handle and a head, bristle tufts on the head, said body being provided with a longitudinal partition defining independent liquid and dentifrice receiving channels extending parallel throughout the length thereof and said head having openings communicating between the bases of the bristle tufts and the channels, there being fewer openings communicating with the dentifrice channel than with the liquid channel, means for leading dentifrice to the dentifrice channel for diffusion through adjacent openings to the bristles tufts, and means for conducting liquid through the liquid channel and opening communicating therewith to mingle with the dentifrice about the bristle tufts.

2. In a tooth brush, a body having a handle and a head, said head having openings therein, funnel-shaped bristle mountings carried in the openings, tufts of bristles having their bases seated in the mountings, said body being provided with a longitudinal partition defining independent liquid and dentifrice receiving channels extending throughout substantially the entire length thereof and being open at the free end of the handle, there being a plurality of openings forming a source of communication between the bristle mountings and the liquid channel and a fewer number of openings connecting the bristle mountings and said dentifrice channel, couplings carried in the open ends of the channels, means for leading dentifrice through the dentifrice channel and certain of the funnel-shaped bristle mountings to the bases of the bristle tufts, and means for leading liquid through liquid channel and through other of the funnel-shaped bristle mountings to mingle with dentifrice on the bristles.

3. In a tooth brush as recited in claim 2, wherein in said last mentioned means is connectable with the first mentioned channel for flushing said first mentioned channel.

ALFRED F. TABORSKI.
